UNITED STATES PATENT OFFICE.

WALTER D'A. RYAN, OF NORTH ADAMS, MASSACHUSETTS, ASSIGNOR TO GENERAL ELECTRIC COMPANY, A CORPORATION OF NEW YORK.

DESIGN FOR A LAMP-FIXTURE.

43,646.

Specification for Design.

Patented Feb. 25, 1913.

Application filed November 16, 1912. Serial No. 731,878. Term of patent 14 years.

To all whom it may concern:

Be it known that I, WALTER D'A. RYAN, a subject of the King of Great Britain, residing at North Adams, county of Berkshire, State of Massachusetts, have invented a new, original, and ornamental Design for Lamp-Fixtures, of which the following is a specification, reference being had to the accompanying drawing, forming a part thereof.

The figure is a side elevation of a lamp fixture showing my new design.

I claim—

The ornamental design for a lamp fixture as shown.

In witness whereof, I have hereunto set my hand this 15th day of November, 1912.

WALTER D'A. RYAN.

Witnesses:

BENJAMIN B. HULL,
HELEN ORFORD.
